UNITED STATES PATENT OFFICE.

ELLSWORTH A. HAWTHORNE, OF SPRINGFIELD, MASSACHUSETTS, ASSIGNOR TO HAWTHORNE AND SHEBLE MANUFACTURING COMPANY, OF PHILADELPHIA, PENNSYLVANIA, A CORPORATION OF PENNSYLVANIA.

DISK-RECORD-FILING CABINET.

No. 887,631.

Specification of Letters Patent.

Patented May 12, 1908.

Application filed May 22, 1908. Serial No. 318,185.

To all whom it may concern:

Be it known that I, ELLSWORTH A. HAWTHORNE, a citizen of the United States, and a resident of Springfield, Massachusetts, have 5 invented certain Improvements in Disk-Record-Filing Cabinets, of which the following is a specification.

My invention consists, primarily, of an adaptation of the book-case unit system to 10 cabinets for the storage of the disk records of talking machines, the invention comprising the combination of a unit case with a plurality of specially constructed sub-units, whereby I secure not only the advantages of 15 ready adjustment of storage capacity to suit the amount of stock on hand, which is a characteristic of the book-case unit system, but I also provide for the convenient and orderly disposition of the various records, 20 for the ready accessibility of the same, and for the quick and accurate distribution of fresh additions to the stock, thereby insuring economy of time and labor not only in distributing new stock, but also in filling the 25 orders of purchasers.

In the accompanying drawing Figure 1 is a perspective view of a unit for a disk record filing cabinet constructed in accordance with my invention; Fig. 2 is a perspective view of 30 one of the sub-units; Fig. 3 is a similar view of a sub-unit without the partitions therein, one of such partitions being shown detached, and Fig. 4 is a transverse section of Fig. 1, but on a somewhat larger scale, and showing, 35 by dotted lines, the outline of one of the disk records.

In Fig. 1 of the drawing, 1 represents the unit casing which is of rectangular form and is open at the front, this casing being of any 40 desired length, depending upon the number of sub-units 2 which it is intended to receive. Each of these sub-units consists of a box or casing with high back 3, low front 4, and sides 5 with inclined or beveled front edges, 45 each of these sub-units also having a false front 6 some distance in the rear of the main front 4, and, by preference, slightly higher than the same, said false front being backed by an inclined strip 7, so that it presents a 50 triangular cross section. In the inner face of the back 3 of each sub-section, at the top of the same, are formed shallow vertical grooves or notches, 9, and in the members 6 and 7 of the false front there are, by preference, corresponding grooves or notches 10,

the two set of grooves or notches receiving and laterally confining the opposite ends of a series of partition strips 12, whereby each sub-unit is divided into a plurality of spaces for the reception of the disk records, each of 60 the partition strips 12, however, being readily detachable, whereby the width of any storage space for the disks can be readily varied to suit the number of disks of any one kind which may be in stock. 65

Owing to the inclined front edges of the side walls of the sub-units and to the inclined disposition of the partition strips therein, the circular disk records deposited in the spaces between the partitions project forwardly beyond said partitions and beyond the sides of the sub-units, and can, therefore, be readily placed in position or withdrawn, while the provision of the main and false fronts 4 and 6, spaced apart from each other, produces a 70 finger space 13 between them, whereby either sub-unit can be readily grasped and pulled outwardly from or pushed back into its position in the main unit even though all of the spaces of said sub-unit are filled with records. 75 80

I claim:—

1. In a disk record filing cabinet the combination of a main unit with a plurality of sub-units fitted therein, side by side, but independently removable therefrom and each 85 constructed for the reception of a plurality of records, and having a main front and a false front in the rear of the same, providing a finger space between them.

2. A sub-unit for a disk record filing cabinet, having a main front and a false front in the rear of the same, providing a finger space between them. 90

3. A sub-unit for a disk record filing cabinet, said sub-unit having a back member 95 with vertical grooves or notches therein, a front member of triangular cross section, and correspondingly notched or grooved, inclined partition strips, having opposite ends adapted to said notches, and a main front in 100 front of said front member, providing a finger space between the same.

In testimony whereof, I have signed my name to this specification, in the presence of two subscribing witnesses.

ELLSWORTH A. HAWTHORNE.
